Application filed January 12, 1882. Term of patent 3½ years.

To all whom it may concern:

Be it known that I, DAVID MCNAIR, of Boston, in the county of Suffolk and State of Massachusetts, have invented a new and original 5 Design for Carpets, of which the following is a specification.
The nature of my design is fully shown in the accompanying photographic illustration.
The design is composed of, first, the irregularly-shaped light-ground centers or figures A, bounded upon one side by heavy floral and foliage ornamentation projecting partially over 10 said center, and having its opposite side more sharply defined by curved lines; secondly, the dark-ground centers or figures B, surrounded 15 by ornamental borders, and provided with flo-

ral ornamentation; and, thirdly, numerous smaller ornamented figures of various forms disposed, as shown, around the larger figures, A B.
